(57) **CLAIM**

The ornamental design for a tub and shower enclosure, as shown and described.

DESCRIPTION

In a preferred embodiment, the nature of this product is an enclosure for a tub and/or shower primarily useful for washing humans.

FIG. 1 is a top, left, front perspective view of a tub and shower enclosure embodying my new design;

FIG. 2 is a top, right, front perspective view thereof;

FIG. 3 is a front elevational view thereof;

FIG. 4 is a top plan view thereof;

FIG. 5 is a left side elevational view thereof;

FIG. 6 is a right side elevational view thereof;

FIG. 7 is a rear elevational view thereof; and,

FIG. 8 is a top, right, front perspective view of a tub and shower enclosure according to another embodiment of my new design, the top, right, front perspective view, front elevational view, top plan view, left side elevational view, right side elevational view, and rear elevational view thereof being mirror images of respective FIGS. 2-7 above.

The broken line representations in the figures are for the purpose of illustration only, and form no part of the claimed design.
